Primary Examiner—Melody N. Brown

(21) Appl. No.: 29/182,216

(74) *Attorney, Agent, or Firm*—Jacob Eisenberg; Siemens Schweiz AG

(22) Filed: May 22, 2003

CLAIM

(30) Foreign Application Priority Data

The ornamental design for a steering wheel, as shown.

Nov. 27, 2002 (DE) 402 09 941

DESCRIPTION

(51) **LOC (7) Cl.** **12-16**
(52) **U.S. Cl.** **D12/176**
(58) **Field of Search** D12/175, 176
74/552, 558, 558.5

FIG. 1 is a front view of an embodiment of a steering wheel;
FIG. 2 is a back view thereof;
FIG. 3 is a bottom view thereof;
FIG. 4 is a top view thereof;
FIG. 5 is a view from the left side thereof; and,
FIG. 6 is a view from the bottom side thereof.
